William Bloomberg, Inventor,
By his Attorney, Robt. B. Killgore.

UNITED STATES PATENT OFFICE.

WILLIAM BLOOMBERG, OF NEW YORK, N. Y.

BUCKLE.

No. 836,176.

Specification of Letters Patent.

Patented Nov. 20, 1906.

Application filed November 2, 1905. Serial No. 285,584.

To all whom it may concern:

Be it known that I, WILLIAM BLOOMBERG, a citizen of the United States, residing at the borough of Brooklyn, city of New York, county of Kings, and State of New York, have invented a new and useful Improvement in Buckles, of which the following is a specification.

My invention relates to improvements in buckles of the lever type in which the web is held between a lever and a back; and the object of my invention is to produce a buckle in which the web may be adjusted either by sliding the buckle along the web passing between the lever and back or by detaching the end of the web from a web-engaging bar and replacing it thereon in a new position. A further object is to obviate all sewing of the web to the buckle.

I attain these objects by the means shown in the accompanying drawings, in which like reference characters designate like parts throughout.

Figure 1 is a front view of a buckle embodying my invention. Fig. 2 is a side view of the structure of Fig. 1. Fig. 3 is a sectional view showing one method of threading the buckle. Fig. 4 is a view, partly in section, showing another method of threading the buckle.

The buckle 1 comprises the usual frame having the lever consisting of the finger-piece 2 and gripping-bar 3, pivotally secured thereto near one end by means of the ears 4. The frame 1 has the back or back bar 5, opposed to the gripping-bar 3 of the lever at one end and at the other the web-retaining or bottom bar 6. The web-engaging bar 7 is secured to the frame 1 between the back 5 and bottom bar 6 and is preferably pivoted or hinged thereto. This bar 7 is provided with web-engaging means, which, as shown, consist of the prongs 8. The upper part of the prongs preferably come behind the finger-piece 2 when the buckle is in closed position, so that they are held flat against the frame. The buckle is used or threaded in either of two ways. First, as shown in Fig. 3, the end 10 of the web is passed between the gripping-bar 3 of the lever and the back 5, where it may be clamped at any desired point. The other end 11 is carried around the buckle, as shown, first between the back 5 and the web-engaging bar 7, as at 12, the prongs 8 piercing and holding the web. The free end of the web 13 is then passed from

front to back between the bottom bar 6 and the web-engaging bar 7, and the threading is then complete without any sewing.

As shown in Fig. 4, one end 14 of the web 60 is secured between the lever and back, and the other end is then carried between the web-engaging bar 7 and the back 5, as indicated at 15, the free end 16 being passed between the web-engaging bar 7 and the bottom bar 6 from the back, where the end is secured without sewing.

It is apparent that the web may be adjusted either by sliding the buckle along the web between the lever and back, clamping it at 70 the desired place, or the free end may be detached from the web-engaging bar and reattached in a new position without any cutting or sewing. This latter feature is advantageous in the manufacture of suspenders, as a 75 short man can shorten up the suspenders without bringing the buckle up to his shoulder or, as it sometimes happens, over on his back.

Having thus described my invention, what 80 I claim as new, and desire to secure by Letters Patent, is—

1. A suspender-buckle comprising a frame; a lever pivotally secured thereto at one end; a back bar in the frame opposed to the clamping edge of the lever when the buckle is 85 closed; a bottom bar in the frame at the other end; a web-engaging bar in the frame between the bottom and back bars; in combination with a web, one end of which is 90 passed around the web-engaging bar and the end placed under the bottom bar to hold it in place, and the other end of which is passed over the front of the buckle between the lever and the back bar whereby it may be 95 clamped at a predetermined point.

2. A suspender-buckle comprising a frame; a lever pivotally secured thereto at one end; a back bar in the frame opposed to the clamping edge of the lever when the buckle is 100 closed; a bottom bar in the frame at the other end; a web-retaining bar in the frame pivotally secured thereto between the back and bottom bars; in combination with a web one end of which is passed around the web- 105 engaging bar and under the bottom bar to hold it in place, and the other end of which is passed over the front of the buckle between the lever and back bar whereby it may be clamped at any desired point.

3. A suspender-buckle comprising a frame; a lever pivotally secured thereto at one end;

a back bar in the frame opposed to the clamping edge of the lever when the buckle is closed; a bottom bar in the frame at the other end; a toothed or pronged web-engaging bar pivotally secured in the frame between the back and bottom bars; in combination with a web one end of which is passed around the web-engaging bar and under the bottom bar to hold it in place and the other end of which is passed over the front of the buckle between the lever and back bar whereby it may be clamped at any desired point.

4. A suspender-buckle comprising a frame; a lever pivotally secured thereto at one end; a back bar in the frame opposed to the clamping edge of the lever when the buckle is closed; a bottom bar in the frame at the other end and a pronged web-engaging bar pivotally secured to the frame between the back and bottom bars adapted to have the end of the web passed around it; the points of the prongs lying against the back bar and under the finger-piece when the buckle is closed.

5. A suspender-buckle composed of a frame, a lever pivotally secured thereto, said frame consisting of a back opposed to the lever, a bottom bar, a web-engaging bar be-

tween the back and bottom bar, in combination with a web passed between the lever and the back, thence between the web-engaging bar and the back, thence between the web-engaging bar and the bottom bar.

6. A suspender-buckle comprising a frame; a lever pivotally secured thereto at one end; a back bar in the frame opposed to the clamping edge of the lever when the buckle is closed; a bottom bar in the frame at the other end; a pronged web-engaging bar pivotally secured to the frame between the back and bottom bars, the points of which lie against the back bar and under the finger-piece of the lever when the buckle is closed; in combination with a piece of web one end of which is passed around the web-engaging bar and under the bottom bar to hold it in place, and the other end of which is passed over the front of the buckle and between the lever and back bar whereby it may be clamped at any desired point.

In testimony whereof I have hereunto subscribed my name, in the presence of two witnesses, this 27th day of October, 1905.

WILLIAM BLOOMBERG.
